UNITED STATES PATENT OFFICE.

PERCY BARRINGTON MEYER, OF LONDON, ENGLAND.

RAIL ANCHOR OR ANTICREEP DEVICE FOR RAILWAY RAILS.

Application filed June 23, 1927, Serial No. 200,945, and in Great Britain August 6, 1926.

This invention consists in an improved rail anchor or anti-creep device for preventing creeping of railway rails.

More particularly the invention relates to 5 an anti-creep device or rail anchor of the type comprising a clip or yoke adapted to embrace the base flange or foot of the rail and a lever member which is fulcrumed on the horizontal portion of the clip that extends transversely below the base flange of 10 the rail, one portion or arm of the lever member abutting against the face of the sleeper and the other portion or arm bearing against the underside of the base flange 15 of the rail when the rail anchor is in its operative position.

An anti-creep device or rail anchor according to this invention is not only simple in construction but is also such that it can 20 be easily and quickly placed in its operative position on the foot or base flange of the rail without having to apply force or hammer blows to move it along the rail base or foot to its operative position in which it abuts 25 against the face of the sleeper on which the rail is mounted. Further a rail anchor according to this invention is such that on creep of the rail taking place the hold or grip of the rail anchor on the base flange or 30 foot of the rail is greatly increased as compared with the hold or grip of rail anchors heretofore usually employed, so that a rail anchor according to this invention is much more effective for preventing creep of the 35 rails. A rail anchor according to this invention is also such that should backward creep of the rail take place (i. e. creep in the opposite direction to that in which creep normally or usually takes place) and carry the rail 40 anchor away from the sleeper, so that its pressure part or member is moved out of contact with the face of the sleeper, the anchor is maintained in proper position on the base flange or foot of the rail and will, as 45 soon as sufficient creep in the normal or forward direction takes place to bring the pressure part or member of the anchor into contact with the face of the sleeper, immediately come into action for increasing the grip 50 or hold of the anchor on the rail base or flange,

Further an anti-creep device or rail anchor according to this invention is such that it bears against the face of the sleeper only at a position well below the top or upper edge 55 of the sleeper even when the rail to which the anchor is applied is carried on a bearing plate on the top of the sleeper; preferably the anchor bears against the face of the sleeper at or below the horizontal centre line 60 of the sleeper.

An anti-creep device or rail anchor according to this invention comprises a yoke or clip adapted to embrace the base flange or foot of the rail, and a member or lever 65 fulcrumed on the horizontal portion of the said clip which lies transversely below the base flange of the rail, the said member or lever comprising a relatively long arm which abuts against the face of the sleeper 70 and a short arm which abuts against the underside of the base flange or foot of the rail when the anchor is mounted in its operative position thereon, the said arms lying on opposite sides of the fulcrum formed by the 75 transverse portion of the clip and the said member or lever being so formed that it extends, preferably with an upward slope or curve, constantly or continuously in the direction away from the face of the sleeper to 80 the end of the short arm of the lever. Thus formed the lever member has more or less the form of an arc.

Preferably the form of the above-mentioned member or lever is such that the edge 85 at the end of the short arm of the lever will tend to bite into the underside of the rail base when, on creep of the rail taking place, the longer arm is pressed with increased force against the face of the sleeper. 90

The aforesaid yoke or clip, which embraces the base flange of the rail may, in general, be similar to the clips or yokes heretofore employed in rail anchors, i. e. it comprises a horizontal portion, which extends transversely below the rail base, and at opposite ends of the said horizontal portion upwardly projecting portions with inwardly bent or hook-like portions adapted to take over and bear upon the upper side of the base flange of the 95 rail. According to this invention, however, in one embodiment thereof, the clip or yoke 100

consists of a length of high tensile steel rod or bar of circular or approximately circular form in cross-section and of appropriate diameter, the said rod or bar being shaped 5 or formed so as to provide the aforesaid upwardly projecting portions with inturned ends. Such a yoke or clip possesses a certain amount of resilience or spring. If desired, however, the rod or bar of which the 10 clip is made may be a spring steel rod.

Further according to this invention, in the preferred embodiment thereof, the upwardly projecting and inturned (or hook-like) part at one side of the clip is so formed 15 that it has an inward projection between its upper end and its lower end which adjoins the horizontal portion of the clip, the said inward projection being provided for the purpose hereinafter set forth.

20 The invention further consists in the rail anchors substantially as hereinafter described with reference to and as illustrated in the accompanying drawing in which,—

Fig. 1 is a side elevation showing a portion of a flat-bottomed rail with a rail anchor according to one embodiment of the invention in operative position on the base flange of the rail.

Fig. 2 is an end view of Fig. 1 looking 30 from the right hand.

Fig. 3 is a similar view to Fig. 2 but shows the position of the rail anchor when it is being applied to the base flange of the rail.

35 Fig. 4 is a similar view to Fig. 2 but shows the rail anchor having the modified form of the clip or yoke hereinafter described.

40 Figs. 5 and 6 are views showing the method of applying the rail anchor with clip, according to Fig. 4, to the base flange of the rail.

Like reference numbers indicate corresponding parts in the several figures of the 45 drawings.

In Figs. 1, 2 and 3, the yoke or clip which embraces the base flange *a* of the rail, when the anchor is in its operative position thereon, comprises the horizontal portion *b* and 50 the upwardly projecting and inwardly turned side or end portions *c* and *d* the inturned or hook-like ends *c'* and *d'* of which rest upon the upper side of the base flange *a* of the rail; *e* is the long or relatively long 55 arm of the hereinbefore-mentioned lever member of the rail anchor and *e'* is the short arm of the said lever, this lever being mounted on the horizontal portion *b* of the clip member so that it can have a rocking 60 movement thereon, the said horizontal portion *b* serving as the fulcrum of the lever. In the embodiment illustrated in the drawings, the lever member consists of a length 65 of steel of standard T-section bent or shaped as shown and having drilled through the

web *e* a hole of sufficient size to permit of the end of one of the inturned portions, for instance *c'*, of the clip member being passed or threaded through the said hole so as to position the lever member on the horizontal portion *b* of the clip member, the said hole in the web *e* being of a somewhat larger diameter than the diameter of the metal of which the clip member is made so as to allow slight clearance between the web *e* of the lever and the horizontal part *b* of the clip. As shown in Fig. 1 the lever curves and slopes upwardly from the lower end of its longer arm *e* to the end of its shorter arm *e'*, the face of the lever at or adjacent to the lower end of its longer arm *e* abutting against the sleeper *f* when the rail anchor is in its operative position as shown in Fig. 1; also as shown in Fig. 1, the upper side or face of the short arm *e'* of the lever abuts or bears against the lower face of the base flange *a* of the rail at a position somewhat beyond the side of the clip member remote from the sleeper *f*. The lever member comprising the long arm *e* and the short arm *e'* is preferably made in the form as shown in Fig. 1, that is to say, with a flat or relatively straight portion *e* between the curved portion or face at or adjacent to the lower end of the long arm *e* and the corresponding curved face or upper side of the short arm *e'*. The hole through the web *e* of the lever member is indicated at *g*.

Referring to Fig. 3 which shows the method of applying the rail anchor as illustrated in Figs. 1 and 2 to the base flange of the rail, the upwardly and inwardly turned side or end portion *c*, *c'* of the member is first hooked over one side of the base flange *a* of the rail, as shown in Fig. 3, whereupon the other upwardly and inwardly turned side or end *d*, *d'* of the clip member is raised and the part *c*, *c'* is lowered, so that the clip takes the position shown in Fig. 2.

With reference to Figs. 4, 5 and 6, in these figures the clip member is, as clearly shown in the drawings, made of different form from that shown in Figs. 1, 2 and 3, the clip member in Figs. 4, 5 and 6 having formed on the inside of the upwardly and inwardly turned side or end portion *d*, *d'* a small projection *h*, and this clip being further so formed as to provide a recess *j* to accommodate the base flange *a* of the rail when applying the anchor thereto as shown in Fig. 5, and a further recess *k* which accommodates or receives the edge of the base flange *a* when the rail anchor is in its operative position thereon as shown in Fig. 4. The shape of the upwardly turned side or end *d* of the rail anchor shown in Figs. 4, 5 and 6 also differs from that of the upwardly turned portion *c* shown in Figs. 2 and 3, the said portion *c* in Figs. 4 and 5 having an outward slope instead of an inward slope as

shown in Figs. 2 and 3. This outward slope is not material, but an inward slope is not required as the recess *j* affords sufficient clearance to permit the clip to be placed in 5 its permanent position.

The lever member comprising long or relatively long and short arms, respectively *e* and *e'*, of the rail anchor shown in Figs. 4, 5 and 6 is in all respects identical with the 10 lever member shown in Figs. 1, 2 and 3.

For placing the rail anchor of Figs. 4, 5 and 6 in its operative position on the base flange *a* of the rail as shown in Fig. 4, the clip member is held in the canted or tilted 15 position shown in Fig. 5 and its side portion *d*², *d*³ is moved laterally towards the base flange of the rail until the edge of the base flange enters as far as possible into the hereinbefore-mentioned recess *j* whereupon 20 the opposite end having the upwardly and inwardly turned portion *c*², *c*³ is raised and the clip member is then moved laterally towards the right into the position shown in Fig. 6 in which the above-mentioned small 25 projection *h* rests on the upper edge of the base flange *a* of the rail. The clip member is now brought into the final position shown in Fig. 4 by giving a hammer blow on the top of the inturned portion *d*³ of the clip 30 which forces the projection *h* down past the edge of the base flange *a* of the rail so that the side of the said flange enters the recess *k* of the clip member, this being the position shown in Fig. 4.

It is to be understood that the distance 35 between the inner side or face of the upwardly turned part *c*² of the clip, against which the side or edge of the base flange *a* of the rail rests as shown in Fig. 4, and the 40 face of the recess *k* in the upwardly turned part *d*², *d*³ is slightly less than the width of the rail base *a* from side to side. Further when the rail anchor is in the position 45 shown in Fig. 4 the clip member will, by its inherent resilience or spring, exert pressure upon and thus grip the sides or edges of the rail base *a*, thereby ensuring against displacement of the clip, for instance by vibrations or by an accidental blow on one of its 50 ends or sides.

As hereinbefore-mentioned the rail anchor illustrated in Figs. 1, 2 and 3 can be very easily and quickly applied to the base flange *a* of the rail and when mounted thereon in 55 the position shown can be easily moved along the base flange of the rail by hand, without the application of any force, to the operative position shown in Fig. 1 in which the lower portion of the longer arm *e* of the lever member abuts against the face of the 60 sleeper *f* and the upper face of the short arm *e'* bears or abuts against the underside of the base flange *a* of the rail as shown in Fig. 1.

The rail anchor with modified form of 65 clip shown in Figs. 4, 5 and 6 can also be very easily and quickly placed in operative position on the base flange of the rail, as with the anchor in the position shown in Fig. 6 if the lower portion of the longer 70 arm *e* of the lever member is not abutting against the sleeper *f* the clip member together with the lever member can be easily moved by hand along the base flange of the rail until the said longer arm of the lever 75 abuts against the sleeper as shown in Fig. 1, whereupon the hammer blow can be struck on the portion *d*³ of the clip (Fig. 6) so as to bring it to the final position shown in Fig. 4.

The rail anchor as above described and shown in the drawings is such that on creep taking place towards the left hand in Fig. 1, the lower portion of the longer arm *e* of the lever member is pressed with increasing 80 force against the face of the sleeper *f* so that the upper side or face of the short arm *e'* of the lever is pressed with great force against the underside of the base flange of the rail, the upper edge of the end of the 85 said short arm *e'* tending under the great pressure applied to bite or be pressed into the base flange of the rail. At the same time the action of the lever when pressed by the 90 creeping of the rail against the face of the sleeper tends to press downwardly the horizontal portion *b* of the clip, thus not only pressing the undersides of the inturned portions *c*² and *d*², Fig. 1, — *c*³, *d*³, Fig. 4, — hard 95 on the upper face of the base flange *a* of the rail, but also tending to contract the clip member so as to draw the side portions (*c*, *d* or *c*², *d*²) laterally towards each other and thus give a firm lateral grip of the clip upon the edges or sides of the base flange of 100 the rail.

Further when applying the rail anchor to the base flange of the rail, no forcible action is required for bringing the short arm *e'* of the lever into contact with the base flange *a* 110 of the rail.

Further with rail anchors according to this invention, should backward creep of the rail take place, that is creep in the direction opposite to that in which creep usually takes place, so that the lower portion or end of the long arm *e* of the lever member is moved out of contact with the face of the sleeper *f*, the lever member *e* of the rail anchor is automatically maintained or retained in its 115 proper position with the upper side or end of the short arm *e'* of the lever in contact with the underside of the base flange *a* of the rail, so that on creep taking place again in the normal direction, sufficient to again press the lower portion of the longer arm *e* of the lever against the face of the sleeper *f*, the lever will be immediately brought into action 120 125

for increasing the grip or hold of the anchor upon the base flange of the rail.

As shown in the drawings the width of the lever member e , e' is much less than the length of the horizontal portion b of the clip or yoke, so that the lever member can, in the action of applying the rail anchor to the base flange of the rail, slide laterally along the horizontal portion b of the clip to one side or end thereof as shown in Figs. 3, 5 and 6 thus facilitating the placing of the rail anchor on the base flange a of the rail and also reducing the length or height of the upturned ends c , c' and d , d' (respectively c^2 , c^3 and d^2 , d^3 , Figs. 4, 5 and 6) and consequently reducing the distance between the underside of the base flange a of the rail and the horizontal portion b of the clip or yoke when same is mounted on the rail base as shown in Figs. 2 and 4.

Although certain forms of construction of the clip member and the lever member have been hereinbefore described and shown in the drawings, it is to be understood that modifications might be made in the form of construction of both the clip and the lever member without departing from the main features of the invention.

For instance instead of the clip or yoke member being circular or approximately circular in cross-section throughout, the metal of which the clip or yoke is made, may be rectangular or square in cross-section with the exception that a predetermined length of the horizontal portion of the clip, which extends transversely below the base flange of the rail, may be circular or approximately circular in cross-section the lever member being mounted or fulcrumed on the said circular portion.

What I claim is:—

1. A rail anchor, comprising a clip for engaging with the rail, and a gripping lever pivoted between its ends upon the clip and having end portions of different length, said lever having a reinforcing member which extends continuously from its long end which engages with the tie to its short end which engages with the rail. 45

2. A rail anchor, comprising a clip for engaging with the rail, and a gripping lever pivoted between its ends upon the clip and having end portions of different length, the short end portion which engages with the rail being arranged wholly to one side of the pivot portion of the clip. 50

3. A rail anchor, comprising a clip for engaging with the rail, and a gripping lever T-shaped in cross-section and having end portions of different lengths, the web of the said lever being pivoted upon the clip and its flanges arranged to bear on the tie and on the rail. 60

4. A rail anchor, comprising a clip formed of a bar of metal of substantially circular cross-section throughout its length and having hook-shaped ends for engaging with the flange of the rail, and a gripping lever pivoted between its ends on the clip. 65

5. A rail anchor, comprising a spring clip having hook-shaped ends for engaging with the rail, one end being provided with two recesses of different depths, the deeper recess permitting the clip to be slid transversely to the rail and the shallow recess being adapted to lock the clip in its permanent position on the rail, and a gripping lever pivoted between its ends on the clip. 70 75

In testimony whereof I affix my signature.
PERCY BARRINGTON MEYER.
